UNITED STATES PATENT OFFICE.

DAVID M. GILBERT, OF NEW YORK, N. Y.

DESIGN FOR A HOOD FOR INCANDESCENT ELECTRIC LAMPS.

SPECIFICATION forming part of Design No. 37,178, dated October 11, 1904.

Application filed November 30, 1903. Serial No. 183,295. Term of patent 7 years.

To all whom it may concern:

Be it known that I, DAVID M. GILBERT, a citizen of the United States, and a resident of Brooklyn borough, New York city, and State of New York, have invented a certain new, original, and ornamental Design for Hoods for Incandescent Lamps, of which the following is a specification.

The accompanying drawing discloses an elevational view of the said hood.

What I claim as new, and desire to secure by Letters Patent, is—

The ornamental design for a hood for incandescent electric lamps, as shown.

DAVID M. GILBERT.
